United States Patent Office

Des. 192,291
Patented Feb. 27, 1962

192,291

FRAMED STRING DECORATION

Neil J. White, Los Angeles, Calif.
(929 W. Spruce St., Inglewood, Calif.)

Filed Dec. 29, 1959, Ser. No. 58,839

Term of patent 14 years

(Cl. D29—23)

Fig. 1

Fig. 2

FIGURE 1 is a plan view of a framed string decoration showing my new design; and

FIGURE 2 is a side elevational view thereof.

The back is plain and unornamented.

I claim:

The ornamental design for a framed string decoration, substantially as shown and described.

References Cited in the file of this patent

UNITED STATES PATENTS

1,910,923 Kerr May 23, 1933
2,824,662 Cole Feb. 25, 1958

OTHER REFERENCES

"Apex" Dart Games, leaflet rec'd Nov. 17, 1948, page 1, center top target No. T-15.

Gift and Art Buyer, April 1950, page 66, panel in upper right corner.

Display World, August 1952, page 51, line illustration on page.

House Beautiful, December 1958, rec'd November 24, 1958, page 146, second circle from top left corner.